UNITED STATES PATENT OFFICE.

ARTHUR RONALD TRIST, OF LONDON, ENGLAND.

DEVICE FOR AUTOMATICALLY STOPPING FEED-WATER PUMPS.

1,187,112.

Specification of Letters Patent. Patented June 13, 1916.

Application filed May 11, 1915. Serial No. 27,316.

To all whom it may concern:

Be it known that I, ARTHUR RONALD TRIST, subject of the King of Great Britain and Ireland, residing in the city of London, 5 England, have invented new and useful Improvements in Devices for Automatically Stopping Feed-Water Pumps, of which the following is a specification.

This invention relates to improvements in 10 governing devices for automatically controlling the supply of feed water to steam boilers and for like purposes of the type claimed and illustrated in the specification of the application filed by me under Serial No. 15 844755 and date the 12th of June 1914 and refers to a modification in the construction of the differential regulator described therein.

The object of the invention is to provide 20 means by which the pump or other pressure producing device can be brought to and maintained in a stationary condition in the event of the pressure in the main falling below a certain amount. It has been found 25 in practice that where such a regulator is used to control the operations of a pump for producing hydraulic pressure, should a pipe or other device fracture or from some other cause the pressure in the hydraulic main 30 suddenly drop, the pump under such circumstances would be suddenly allowed to run away with a consequent risk of mechanical break down on the one hand and on the other hand of a grave possibility of 35 flooding.

To carry the invention into effect I arrange a detent which will co-act with the control device (such as the steam valve) and is adapted to be normally kept out of operation by a yielding force such as a weight or a spring. When however the power device is allowed to return under its own spring owing to the drop in pressure and has reached a predetermined point in its 45 travel it engages with said detent and moves it into the position of closing the steam valve and maintaining it in such a position until again released by hand or by pressure coming on the main again by the 50 operation of the pump by an independent source of steam supply.

Referring to the drawing which forms part of this specification and which shows the upper part of a governor of the type 55 hereinbefore referred to with this invention

applied thereto, the rod *a* of the power device which has an adjustable yielding resistance such as a spring *b* is provided with an adjustable collar *c*. Upon a fulcrum pin *d* carried by the frame of the governor is pivotally mounted a detent lever *e* which is stressed by a spring *f* or other elastic or yielding force. The lower end of the lever *e* is of curved shape so as to engage with the collar *g* at the upper end of 60 the spindle *h* controlling the steam pump. The lever *e* also carries a pin or roller *j* which lies in the path of the collar *c*. When the pressure goes off the power device the spring *b* causes the collar *c* to rise and contacting with the roller or pin *j* draws the lower end of the lever *e* into the position indicated in dotted lines so that it contacts with the collar *g* and forces down the spindle *h* and stops the steam pump. When 65 the pressure comes on the main again the collar *c* moves downward and allows the spring *f* to withdraw the lever *e* and permits the spindle *h* to put the pump again 70 into motion; but until the lever *e* is withdrawn from its operative position and thus returned to the position indicated in full 75 lines in the drawing by hand or steam is admitted to the pump by some independent means such as a bypass, the spindle *h* is 80 kept in a locked position. When the proper pressure is on the main the lever *e* is quite 85 inoperative.

I claim:

In combination with a pressure controlled 90 governing device of the type described, having a controlling spindle, a fixed support, a movable detent, cam shaped as to its lower portion, pivoted intermediate of its ends upon said fixed support, a collar on the upper end of said controlling spindle adapted 95 to engage with the cam shaped portion of the detent, means operated by the governing device to engage said detent and bring it into operative engagement with said collar, 100 and means to normally hold the detent in inoperative position.

In testimony whereof I have signed my name to this specification in the presence of two subscribing witnesses.

ARTHUR RONALD TRIST.
